UNITED STATES PATENT OFFICE

2,486,514

YARN WINDER

Helen Boehnke, Round Lake, Ill.

Application July 8, 1947, Serial No. 759,622

2 Claims. (Cl. 242—2)

1

My invention relates to yarn winders, an important object of which is to provide a mechanism by means of which skeins of yarn may be wound upon spools in readiness for knitting.

A further object of my invention is to provide a yarn winder having adjustable arms that may be set to hold a varied number of standard skeins of yarn, or which may be folded up against the side of the yarn winder out of the way when not in use.

A further object of my invention is to provide a yarn winder having a pinion and crank arrangement whereby the yarn may be wound from skeins onto spools mounted detachably on the said yarn winder.

A still further object of my invention is to provide a yarn winder having detachable spools which may be reversed and used to knit from, a number being provided to enable the knitter to knit with different colors of yarn when desirable.

A still further object of my invention is to provide the yarn holding spool, made in two parts, and held together by a bayonet type lock in order that balls of yarn may be easily and quickly placed on the spool in readiness for knitting.

A still further object of my invention is to provide a yarn winder, the rods and spindles of which may be easily detached and placed in the interior of the central tube when not in use, and having one end of the spool countersunk to fit over the end of the central tube to act as a cap.

Other objects and advantages inherent in my invention will become readily apparent from the ensuing description and the accompanying drawings, in which like parts are designated by like numerals, and in which:

Fig. 1 represents a front view of my invention broken to show its principal working mechanism.

Fig. 2 is a cross-sectional view of my invention taken substantially on lines 2—2 of Fig. 1.

Fig. 3 is a cross-sectional view of a portion of my invention taken substantially on lines 3—3 of Fig. 1.

Fig. 4 is a cross-sectional view of a portion of my invention taken substantially on lines 4—4 of Fig. 2.

Fig. 5 is a cross-sectional view of a fragment of my invention taken substantially on lines 5—5 of Fig. 1.

Referring to the illustrations, my invention is generally designated 6 and consists of an upright tubular construction 7 having a base 8, and a

2

flange formation 9 a short distance above the base.

A sleeve 10 is rotatably mounted upon tube 7. The lower end of sleeve 10 is formed into a flange 11, which rides upon ball bearings 12, mounted within a suitable recess in the flanges 9 and 11. The top end of the sleeve 10 is formed into an annular gear 13, and the sleeve is held rotatably in place on the tube 7 by a collar 58. An opening 14 is tapped into the tube 7, just above the annular gear 13, to receive the threaded end 15 of the rod 16 which is provided with a shoulder 17. The other end of the rod 16 is provided with a flattened finger grip 29 for easy assembling. A pin 18 is set at right angles into the rod 16 at a point near its end so that, when the rod 16 is turned tightly into the tube 7, the pin 18 will be vertical and on the top side of the rod 16. A spindle 19 is pivoted frictionally at 20 to the pin 18 so that it will remain in an upright position when in use, or may be angularly articulated to a position parallel with the rod 16 when not in use.

A sleeve 22 rotates upon the rod 16 and has its two ends formed into annular gears 23 and 24, gear 23 meshing with the annular gear 13 on sleeve 10. A collar 25 on the rod 16 holds the sleeve 22 in place. The second sleeve 26 is rotatably mounted on the outer end of the rod 16 and has its inner end formed into an annular gear 27. The sleeve 26 is held in place by a collar 28 on the outer end of the rod 16. Articulately mounted on the sleeve 26 is a crank 30. The crank 30 being frictionally mounted at 31 in order that it may be maintained either in an open working position, as shown in Figs. 1 and 3, or may be angularly articulated to a position parallel with the rod 16 when not in use, as shown by dotted lines in Fig. 1.

A spool split at 33 is provided and the two halves 32 and 34 are connected and kept locked by a bayonet type lock 35. The spool 32 rotates upon the spindle 19 by means of a central bore 36 and also has mounted, on its lower end, an annular gear 37. The spool 32 rests upon a shoulder 21 on the spindle 19 at a point so that the annular gear 37 is enmeshed with the annular gear 24 on sleeve 22 and the annular gear 27 of sleeve 26. A wire guide 49 is threaded into a suitably tapped opening at the top of the tube 7, so that its loop end 50 will be in alignment with the center of the spool 32 when it is mounted on the spindle 19.

A number of semi-circular brackets 39 are attached to the outer circumference of the sleeve

10 at regular intervals just above the flange 11. The two parallel sides of the bracket 39 are peened inwardly at 40 and, in the peened over edges 40, are formed three sets of notches 41, 42, and 43, as shown in Fig. 4. A number of S-shaped arms 44 are articulately mounted in the brackets 39 at 45. The outer end of the arms 44 being bent into a U-shaped conformation 46.

The diameter of the arms 44 is such that they may be maintained in any one of the three notched formations 41, 42, or 43. The sides of the brackets 39 being resilient enough to allow the arms 44 to be changed from one position to another as desired. The notch 41 maintains the arm in approximately a horizontal position, in which position they will accommodate in their end formations 46, a larger skein of yarn, designated 47. The notches 42 are so located as to maintain the arms 44 in an angular position of about 45°, so that their outer formations 46 will accommodate the second and smaller size skeins of yarn, designated 48. The third notch 43 is so located as to maintain the arms 44 in a collapsed position, as shown by dotted lines in Fig. 1.

A number of tapped openings 51 may be provided in the tube 7 in alignment with the tapped opening 14. A number of rods 52 are secured to the tube 7 through the tapped openings 51 in a manner similar to that of the rod 16, the end of the rod 52 being articulately connected to spindle 53; the spindle 53 being made similar to the spindle 19 mounted on the rod 16. The half of the spool, designated 34, is countersunk at 38 to a diameter that will allow the spool to be fitted over the end of the tube 7 and a groove 56 in the countersunk portion 38, together with the pin 55 in the end of the tube 7, provides a bayonet type lock for the spool 32 when it is used as a cap to the tube 7.

To use the yarn winder, a skein of yarn, either the larger size 47 or the smaller size 48, is draped over the arms 44 at their outer ends 46; the free end of the yarn 59 is passed through the loop 50 of the wire 49 and started upon the spool 32 resting on the spindle 19, or the end 59 may be clamped between the surfaces of the split portion 33. By means of the meshing annular gears 13, 23, 24, 27, and 31, the turning of the crank 30 will cause the spool 32 to rotate in the direction of the arrows 60 in Fig. 2, and the arms 44 mounted upon sleeve 10 to rotate in the direction of the arrows 61 in Fig. 2.

A proper ratio between annular gears 13 and 23 will cause the rotating spool 32 to take up and wind the strand 59 of yarn from the skein 47 as it is unwound from the oppositely rotating arms 44. When the skein of yarn 47 has been completely wound upon the spool 32, the spool may be reversed upon its spindle 19 and used to knit from, as shown on the left-hand spindle 53 in Fig. 1.

If it is desired to use a number of differently colored yarns in knitting, one or more of the rods 52, with their attached spindle 53, may be secured to the central tube 7 in the manner previously described, and spools 32 may be mounted to freely rotate upon the spindle 53 in the manner of the spool 32 rotating upon the spindle 19. Yarn that

5 is already wound into a ball 54 may be placed upon the spool 32 simply by twisting the half 34 and separating the halves 32 and 34 by placing the balled yarn upon one of the halves and re-engaging the two halves of the spool by a turn of the bayonet lock.

10 When not in use, the rod 19 with its assembled parts and the rods 52 may be inserted into the interior 57 of the tube 7, and a spool 32 may be tightened over the top of the tube 7, in the manner previously described, to act as a cap. The arms 44 may be folded up against the sides of the sleeve 7, making a compact unit, which will take up very little space when not in use.

15 Other structures may be employed embodying the features of my invention instead of the one here described, change being made in the form or construction, provided the elements stated in any of the appended claims, or the equivalents thereof, be employed.

20 Having thus disclosed and revealed my invention, what I claim as novel and desire to secure by Letters Patent is:

25 1. A yarn winder of the character described comprising, a support, a sleeve rotatably mounted on the said support and terminating in an annular gear portion, a horizontal arm removably secured to the said support and having a perpendicular spool spindle secured thereto, an intermediate pinion secured rotatably to the said spindle, a sleeve having termini formed into pinion portions rotatably mounted on the said horizontal arm and in meshing relationship with the said annular gear portion and the said intermediate pinion, a pinion sleeve rotatably secured to the said horizontal arm and in meshing engagement with the said intermediate pinion, and a handle articulately secured to the said pinion sleeve.

30 40 2. A yarn winder of the character described comprising, a support, a sleeve rotatably mounted on the said support and terminating in an annular gear portion, a horizontal arm removably secured to the said support and having a perpendicular spool spindle secured thereto, an intermediate pinion secured rotatably to the said spindle, a sleeve having termini formed into pinion portions rotatably mounted on the said horizontal arm and in meshing relationship with the said annular gear portion and the said intermediate pinion, a pinion sleeve rotatably secured to the said horizontal arm and in meshing engagement with the said intermediate pinion, a handle articulately secured to the said pinion sleeve, and a yarn winding spool frictionally and removably engageable by the said intermediate pinion.

35 HELEN BOEHNKE.
